WASTE CAN CLOSURE OPERATOR AND SUPPORT

Bertis F. Hamilton, Columbus, Ind.

Application March 14, 1947, Serial No. 734,743

4 Claims. (Cl. 248—147)

1

My invention relates to waste cans of the type made primarily for use in kitchens. Such cans commonly comprise an exterior shell and an interior container which can be withdrawn from the shell; and the shell is frequently provided with a pedal-operated lid. As most usually made, the shell of such devices, together with the lid, forms a complete enclosure for the container.

It is the object of my invention to improve and simplify a waste can of the type described. A further object of my invention is to improve the appearance and capacity of a waste can and to facilitate the withdrawal of the container from the shell.

In carrying out my invention, I form the shell with side and back walls only, leaving the front and top of the shell open. A shelf disposed above the bottom of the back and side walls provides a support for the container, which is received between the side walls and may project forwardly and upwardly therebeyond. A lid or cover for the container is hinged to the upper end of the back wall and operated by a pedal disposed beneath the container-supporting shelf.

The accompanying drawings illustrate my invention: Fig. 1 is a front elevation of the complete waste can; Fig. 2 is a side elevation of the waste can with the lid shown in full lines in closed position and in dotted lines in open position; Fig. 3 is a plan view of the complete can with portions of the lid broken away; Fig. 4 is a horizontal section on the line 4—4 of Fig. 2; and Fig. 5 is an isometric view illustrating a detail of construction.

The can shown in the drawing embodies a shell 10 and a container 11, designated in their respective entireties by the reference numerals 10 and 11. The shell 10 comprises a back wall 12 and opposed side walls 13, all conveniently formed of sheet-metal. As shown, the side walls 13 are provided at their rear edges with inwardly extending flanges 14, which are secured to the back wall 12, as by rivets 15. The back wall 12 terminates above the bottom of the side walls 13, and its lower end is bent inwardly of the shell to form a horizontally extending shelf 16. Below the shelf 16, the lower edges of the side walls 13 are bent inwardly to form flanges 18, which may be secured to the bottom 19 as by means of rivets 20.

Extending between the side walls 13 at the front thereof is a sheet-metal stamping designated in its entirety by the reference numeral 22 and including a horizontal portion 23 forming

2

a supplementary shelf coplanar with the shelf 16 and cooperating therewith to form a support for the container 11. An upwardly projecting flange 24 extends along the front and ends of the supplementary shelf 23 to retain the container 11 in place.

A lid 26 is hingedly connected on a horizontal axis on the upper end of the back wall 12 of the shell, conveniently through the medium of the piano-type hinge 27 shown in Figs. 2 and 3. Such lid is formed to fit over the open upper end of the container 11, the front and side walls of which are desirably offset inwardly to provide a shoulder 28 upon which the lid 26 may rest.

For the purpose of operating the lid 26, it is provided near the rear ends of its side walls with downwardly projecting arms 30 rigidly secured to the lid and connected respectively by links 31 with a pedal 32 pivotally mounted in the shell beneath the shelves 16 and 23. The pedal 32, as will be clear from Fig. 4, is desirably formed from a length of round metal rod bent into a general U-shape to provide an intermediate leg 33 and sides having outwardly offset portions 34 located opposite to and coplanar with each other. The offsets 34 afford a means by which the pedal may be pivotally connected to the shell 10. To this end, the stamping 22 may be provided at its ends with wings 36 which extend inwardly along the side walls 13 of the shell 10 and which include inwardly offset portions 37 having sector-shaped openings 38 respectively receiving the offset portions 34 on the sides of the pedal 32. For the purpose of securing the stamping 22 in place, the wings 36 may be provided along their lower edges with ears 40 bent into a horizontal plane to lie on the flanges 18 of the side walls 13 and to be secured thereto by rivets 20. The ends of the rod from which the pedal 32 is formed are bent outwardly and are pivotally received in holes in the lower ends of the links 31. The fulcrum-forming offsets 34 are put in place in the openings 38 before the stamping 22 is placed in the shell 10.

At its upper end, the container 11 is provided exteriorly and on opposite sides with brackets 42 which pivotally receive the in-bent ends of a carrying yoke or bail 43. In its normal position, the bail 43 extends generally horizontally and forwardly from the brackets 42, being supported in such position against the force of gravity by a bracket 44 secured to the front wall of the container 11. To provide clearance for the brackets 42 and bail 43, the upper front corners of the side walls 13 are relieved. Such

relief may be relatively severe, as indicated in Fig. 2, the front edge of each side wall curving upwardly and rearwardly from a point adjacent the stamping 22 to the upper rear corner of the side wall. To improve appearance, the front edge of the side wall may be bent inwardly on a substantial radius, as indicated at 46 in Fig. 4, and thence rearwardly to provide a flange 47. The flanges 47 on the two side walls are desirably parallel with each other and serve to engage the side walls of the container 11 to locate it properly in a vertical position in which it will not interfere with movements of the links 31. At the top of the shell, the inwardly curved portion 46 and the flange 47 are notched, as indicated at 50 in Fig. 3, to provide clearance for the links 31 and arms 30 on the lid 26.

The pedal 32 is so formed that in the assembled can, its intermediate leg 33 projects forwardly beyond the stamping 22 so that an operator, by stepping on the intermediate portion 33, can depress it to rotate the pedal in a counter-clockwise direction (Fig. 2) thus moving the links 31 upwardly and raising the lid 26. Desirably, the pedal 32 is arranged to swing far enough to move the lid through and beyond the vertical position, whereby the force of gravity acting on the lid will prevent it from returning to its normal closed position. Movement of the lid beyond the dotted-line position shown in Fig. 2 is prevented by engagement of the rear portions of the offsets 34 with the upper edge of the openings 38 in the stampings 22, or by engagement of the intermediate pedal-portion 33 with the floor.

Raising of the lid 26 frees the container 11 for removal from the shell 10, the bail 43 being employed to so remove the container. It is not necessary in the withdrawal of the container 11 to move it upwardly for the full height of the shell 10; for after the container has been raised far enough to clear the flange 24 on the stamping 22, it can be withdrawn forwardly from the shell. Because the bail 43 and the bail-mounting brackets 42 are located entirely outside the shell 10 when the container is in place therein, their presence does not require any reduction in the size of the container. The fact that the container 11 extends upwardly beyond the front and side portions of the shell lessens the possibility that waste matter will drop into the space between the container and shell rather than into the container itself and results in making the bail readily accessible.

I claim as my invention:

1. Means for raising the lid of an open-topped container, comprising a pedal operatively connected to said lid and formed of a rod bent into a general U-shape to provide an intermediate foot-receiving leg and side portions, said side portions being bent to provide aligned, outwardly projecting, U-shaped, fulcrum-forming offsets, and means located outwardly beyond the unoffset parts of said side portions movably receiv-

ing said offsets to permit rocking of the pedal thereabout.

2. In a device of the type described, a shell having side and back walls and being open at its front and top, a container received in said shell and adapted to be withdrawn therefrom through the open front and top thereof, said container having an open upper end, a lid for closing the upper end of said container, said lid being pivotally supported on said shell adjacent the upper end of the back wall thereof, at least one of the walls of said shell being spaced outwardly from said container, and means for swinging said lid about its axis of pivotal support, said means comprising a lid-swinging link connected to said lid at an eccentric point and extending downwardly through the space between such container and shell-wall, and a pedal movably mounted near the bottom of said shell and operatively connected to the lower end of said link to effect lid-swinging movement of said link.

3. In a device of the type described, a shell having side and back walls and being open at its front and top, a container received in said shell and adapted to be withdrawn therefrom through the open front and top thereof, said container having an open upper end, a lid for closing the upper end of said container, said lid being pivotally supported from said shell adjacent the upper end of the back wall thereof, the two side walls of said shell being spaced outwardly from said container, links connected to said lid in front of its axis of pivotal support on the shell and extending downwardly through the spaces between the container and the side walls of the shell, a U-shaped pedal having an intermediate foot-receiving portion and side portions pivoted at intermediate points to said shell, the ends of said side portions being operatively connected to said links whereby depression of said foot-receiving portion will elevate said lid.

4. The invention set forth in claim 3 with the addition that said side walls are provided along their edges with inwardly directed flanges extending toward the container to conceal the links.
